UNITED STATES PATENT OFFICE

2,414,671

FOLDING DISPLAY BOX

Nathan Rosenthal, St. Louis, Mo., assignor to
 Rosenthal Paper Company, St. Louis, Mo., a
 corporation of Missouri

Application April 15, 1944, Serial No. 531,145

1 Claim. (Cl. 206—44)

1

This invention relates to folding boxes of the type having an integral cover and body and has for its principal object to adapt such a box to display purposes. The invention is an improvement on the box of Rosenthal and Wegusen Patent No. 2,090,375 dated August 17, 1937, enabling the box of that patent to be used for display purposes. The invention consists in the folding display box and in the parts and combinations and arrangements of parts hereinafter described and claimed.

In the accompanying drawings, wherein like reference characters indicate like parts wherever they occur,

Fig. 1 is a plan of the blank from which the box is made,

Fig. 2 is a plan view of the marginal portion of the blank after the first folding operation,

Fig. 3 is a plan view of the marginal portion of the blank after the second folding operation,

Fig. 4 is a perspective view showing the stage in the operation of setting up the box at which the side walls and outer end walls have been raised and prior to the interlocking of the strips which reinforce the hinge end of the box,

Fig. 5 is a view similar to Fig. 4, with the cover completely set up and with the reinforcing strips in interlocked position, the body of the box being shown in section and portions of the end wall and cover being broken away to show the reinforcing strips in position,

Fig. 6 is a side elevation, on a reduced scale, showing the set-up box with the cover about to be closed over the body,

Fig. 7 is a side elevation of the assembled and closed box,

Fig. 8 is a perspective view of the box with the cover folded back and under the body to make a display container,

Fig. 9 is a sectional view on the line 9—9 in Fig. 8; and

Fig. 10 is a perspective view of a modified display arrangement, wherein the cover is folded into the box body to make a V-shaped display rack.

The blank illustrated in Fig. 1 comprises a relatively long middle portion A, that makes up the body, cover and end wall portions of the box and two side portions B which terminate short of each end of the middle portion. This blank has four longitudinal scores disposed in two pairs or groups of two, namely 1 and 3, and 2 and 4 and eight transverse scores 5, 6, 7, 8, 9, 10, 11 and 12 which divide the blank into a number of rectangles or panels.

2

The panel C between transverse scores 8 and 9 constitutes the bottom of the box. The panel D, between transverse scores 10 and 11, constitutes the top or cover of the box. The panel E between transverse scores 9 and 10 constitutes a side or end wall to which said bottom C and said cover D are hingedly secured. Panel F, between transverse scores 7 and 8, constitutes the outer wall of a side or end, hereinafter called "free end" of the body. Panel G between transverse scores 11 and 12 constitutes the outer wall of a side or end (hereinafter called "free end") of the cover D, said panels F and G being opposite said hinged wall E. Panel H, between transverse scores 5 and 6, contiguous with the panel F of the body, constitutes the inner wall of said end. Panel J, between transverse scores 6 and 12, contiguous with the free end of the cover constitutes the inner side wall thereof. The narrow rectangle K is a flap that is defined by the transverse score 5 and which, in the setup position of the box, rests on the bottom C thereof with its ends under the inner wall members of the adjacent side of the body. Similarly, the narrow rectangle L constitutes a flap attached to the inner end wall J of the cover and, in the setup position of the box, rests against the inside of the cover D with its ends under the inner wall members of the adjacent sides of the cover. As so far described, the arrangement of score lines and panels is as set forth in said Patent No. 2,090,375.

The present blank has an additional transverse score 13 which divides the cover panel D of the box into two parts d^1 and d^2 . It is this transverse score 13 with the resulting subdivision of the cover panel D that permits the manipulation of the cover of the box into various display positions, as will be hereinafter described.

Two of the longitudinal scores 1, 2, separate the middle portion A of the blank from the respective side portions B. The other two longitudinal scores 3, 4, are near the middle of said side portions but slightly closer to the free side edges than to the middle portion of the blank.

Two of the transverse scores, 5, 6, are located close to the respective ends of the middle portion of the blank to form the narrow locking strips K and L above described. The other six transverse scores are divided into three groups, 7 and 8, 9 and 10, and 11 and 12, the scores of each group being spaced apart the same distance as the two adjacent longitudinal scores 1, 3, are spaced apart and slightly more than the distance of either endmost score 5 or 6 and the transverse score 1 or 12, closest thereto.

The score lines 1 and 2 extending along the edges of the middle portion A of the blank are each interrupted by a slit 14 extending in alignment with the two portions of said score lines 1 and 2 from a point at the junction of the bottom C with the hinge wall E of the box to a point along the margin of the cover portion D of the blank. A transverse slit 15 extends from the end of each longitudinal slit completely across each side portion of the blank, thus interrupting the slits 3 and 4 in the side members B of the blank. The outermost narrow panels M and N alongside the bottom panel C fold over on the innermost narrow panels O and P to form double side walls and the panels Q and R, S and T extending therewith along the hinge end E and part of the cover D are likewise folded together to form double strips hingedly secured to said side walls and adapted to reinforce the hinge end of the box. One strip has a notch 16 in the upper edges of both plies Q and S cooperating with a notch 17 in the lower edges of the plies of the other strip so that the two strips may be interlocked.

The outermost narrow panels U and V adjacent the cover are folded over against the innermost panels W and X to form double side walls extending a part only of the length of the cover D. Small rectangles Y in the corners between the free end walls F and G and the adjacent side walls have diagonal scores 18 whereby they may be folded to form a hinge connection between the bottom C and its free end wall F and the cover D and its free end wall G. The panels have locking tongues 19 projecting therefrom and their edges are provided with triangular flaps 20 formed by score lines 21, for interlocking with the narrow flaps K and L on the end members. Preferably the panels M and N are secured to the panels O and P, as by adhesive, indicated by stippling, as are the panels Q and R to the panels S and T and the panels U and V to the panels W and X, said above mentioned triangular locking projections 20 being free of adhesive or other securing means. Similarly, the portions of the end hinge rectangles Y adjacent to the end walls are secured to said end walls, as by adhesive, indicated by stippling.

After the several side panel members have been folded together to form side walls and locking strips, as above described and as shown in Fig. 2, the doubled members are folded over onto the body or middle portion of the blank, as shown in Fig. 3, the several small hinge rectangles Y being then secured to the blank. The box is now ready to set up, which is accomplished by raising the free end walls F and G of the body and cover, which action, because of the hinge connections Y also raises the side members and locking strips. The side members MO, NP are held in position by folding over the panels H and J against the body C and cover D of the box and interlocking the narrow strips K and L with the adjacent side wall members.

As shown in Fig. 4, the locking strips QS, RT are bent slightly outwardly to permit the raising of the hinge wall E and the locking strips are then interlocked behind said hinge wall. After the merchandise has been placed in the body of the box, the cover D is folded over, as shown in Figs. 6 and 7.

The container may be used for display purposes in various ways. Thus, as shown in Figs. 8, 9 and 10, the cover member is bent around the hinge wall E, the panel d² overlapping the locking strips QS, RT and the width of said panel being slightly greater than the height of said hinge wall, to permit the cover D to be folded under against the bottom C of the box. The box may then be positioned at an angle, supported by the corners 22 of the folded under side walls of the cover.

The display arrangement just described, permits display of the contents of the package in their original position. After some of the contents have been sold, or if, for any other reason, it is desired to use a slightly different form of display, the cover may be folded inwardly about the score line 13 and the corner portions 22 of the side walls UW, VX of the cover supported in the bottom of the box body, as shown in Fig. 10. This creates a V-shaped rack or tray for displaying merchandise.

The above described box has the important advantage of permitting display of merchandise in the original package, while, at the same time, the box has all the important advantages of the integral cover and box construction of said Patent No. 2,090,375.

Obviously, numerous changes may be made without departing from the invention and I do not wish to be limited to the precise construction shown.

What I claim is:

A folding display box comprising a bottom, two-ply side walls secured to said bottom, a two-ply free end wall having its outer ply connected to said bottom and to the outer plies of said side walls to form closed corners therewith, a cover hingedly secured to said hinge end wall, said cover having a multi-ply free end wall and two-ply partial side walls having their outer plies connected to said cover and to the outer plies of said free end wall to form closed corners therewith and extending from said free end wall along a portion of said cover and portions extending from both plies of said two-ply body side walls to form two-ply locking strips, free of said hinge end wall and said cover and interlocked alongside of said hinge wall, said cover having a foldable sub-panel portion whereby said cover may be folded with its major portion under the bottom of the box.

NATHAN ROSENTHAL.
